ATTORNEY

UNITED STATES PATENT OFFICE.

GEROW KOONS, OF ST. LOUIS, MISSOURI.

STEAM WASHING-MACHINE.

SPECIFICATION forming part of Letters Patent No. 326,875, dated September 22, 1885.

Application filed October 11, 1884. (No model.)

To all whom it may concern:

Be it known that I, GEROW KOONS, of St. Louis, in the county of St. Louis and State of Missouri, have invented certain new and useful Improvements in Steam Washing-Machines; and I do hereby declare that the following is a full, clear, and exact description thereof, reference being had to the accompanying drawings, and to the letters of reference 10 marked thereon, which form part of this specification.

This invention relates to certain improvements in boilers for scalding, boiling, and steaming clothes; and it has for its object to provide an improved apparatus wherein clothes may be thoroughly subjected to the action of the hot water and steam, and agitated and scrubbed during the operation, as more fully hereinafter specified.

20 The invention consists in the construction and novel arrangement of parts hereinafter described, and pointed out in the appended claims.

In the accompanying drawings, Figure 1 25 represents a transverse vertical sectional view of my apparatus entire, and Fig. 2 a longitudinal vertical sectional view thereof.

The letter A indicates the boiler, which consists of a rectangular vessel of metal or other 30 suitable material.

B indicates a false bottom, which is semi-cylindrical in shape, and is provided with legs D, upon which it rests when in place in the boiler. Said false bottom is of such size that 35 the edges approach nearly to the upper edges of the boiler, the said upper edges of the boiler being provided with deflecting-flanges E, to direct steam escaping between the upper edges of the false bottom and the boiler into and 40 through the reticulated steam wheel or cylinder, as presently described.

The false bottom is provided below with a series of perforations, F, in order that the water in the boiler may be at the same level above and 45 below said false bottom, and near the upper edges of the said false bottom is a series of apertures, G, through which the steam escapes forcibly into and through the meshes of the steam wheel or cylinder and into and through 50 the clothes contained therein, as more fully hereinafter specified.

The letter H indicates the steam wheel or cylinder, which is constructed of wire-gauze or reticulated metal, in two parts which are hinged together, so that they may be fully 55 opened for insertion of the clothes, the said parts being provided with suitable fastening devices, by which they may be locked together after the clothes are inserted. The wheel or cylinder has formed on the inside at proper 60 intervals V-shaped flanges I, which serve to throw the clothes toward the center of the cylinder or wheel as it rotates, and thus agitate and scrub the same. The wheel or cylinder is mounted upon journals L, which have their 65 bearings at the ends of the boiler, one of said journals being extended and provided with a crank, by means of which the wheel or cylinder may be rotated.

The operation of my invention will be readily understood from the above description. 70

The false bottom and cylinder or wheel being properly secured in the boiler, said boiler is charged with water up to the line *xx*, Fig. 1. Heat is then applied in any convenient manner until the generation of steam commences, 75 the clothes having been previously placed in the steam wheel or cylinder. The cylinder is then rotated, its lower portion passing through the water above the lower portion of 80 the false bottom, while the escaping steam is forced through the upper aperture in said bottom and between the edges of the same into and through the clothes, which are tumbled and scrubbed by the V-shaped flanges 85 during the operation.

Having described my invention, I claim—

1. The combination, in a steam washing-machine, with the rectangular boiler A, provided along its upper front and rear edges 90 with the deflecting-flanges E E, and the foraminous cylinder H, made in two parts hinged together, provided with the inward projections I, and journaled in the sides of the boiler, of the semi-cylindrical false bottom B, 95 supported in the boiler concentric with the wheel H, provided at its lower part with the openings F, and having its edges beveled and separated sufficiently from the deflecting-flanges E to allow the steam to be driven between the two into the lower part of the wheel H, substantially as specified. 100

2. In a washing-machine, the combination, with the boiler A, provided with the deflectors E, and the cylinder H, journaled in the boiler, of the false bottom B, concentric with the said 5 wheel, having its edge beveled to correspond to the deflecting-surfaces of the flanges E, and provided with the openings F and G, the latter of which are adapted to have ascending steam forced through them by the contraction

of the space between the false bottom and the boiler, substantially as described.

In testimony that I claim the foregoing as my own I affix my signature in presence of two witnesses.

GEROW KOONS.
